SEWING MACHINE

George Sauer, Chicago, Ill., assignor to Union
Special Machine Company, Chicago, Ill., a cor-
poration of Illinois

Application May 12, 1942, Serial No. 442,585

5 Claims. (Cl. 112—218)

1

This invention relates to an improved sewing machine construction and more particularly to a power-driven sewing machine having associated therewith means for delivering a blast of cooling air into the region through which the needle or needles operate. A substantial increase in the speed of operation of the machine is made possible by the cooling action of such a blast.

As pointed out in the pending application of Charles F. Rubel, Serial No. 433,740, filed March 7, 1942, the speed of operation of many industrial sewing machines is limited by the tendency of the needles to become overheated. Overheating of the needles not only produces deleterious effects upon the needles themselves, shortening their lives, but also frequently causes damage to other portions of the machine, such as the loop takers. Moreover, it greatly increases the frequency of breakage of the needle thread and thus necessitates rethreading at more frequent intervals with consequent loss of operating time. This overheating tendency is particularly serious when the machine is operating upon heavier fabrics, such as denim, army twill, coated fabrics, and the like. For a fuller discussion of the evils of needle overheating in the operation of a machine, reference may be had to said pending Rubel application.

A primary object of the present invention has been to provide a construction and arrangement of various means by which a blast of cooling air is generated upon the operation of the driving motor of the machine and is delivered to the zone of operation of the needle or needles. This construction and arrangement is such that the various parts may be easily manufactured at a minimum of cost and with the requirement of little or no special tool equipment. Toward this end, a feature of the invention is in the provision of a blower, all of the components of which may be formed from regular stock materials without the necessity of special tools. The blower housing may, for example, be formed of bar stock suitably cut and shaped to form the major portion of the housing and having applied thereto, by welding or the like, suitable adjuncts which are similarly formed from bar stock. While the housing is preferably made of steel or other metal, it may, if desired, be formed of suitable plastic materials.

Another feature of the blower is the production of the rotor element from a flat sheet or steel or the like by simply cutting out and bending up appropriate portions of the sheet to form vanes. The vane element so formed is preferably united with a backing sheet or disc which serves to eliminate vibration or weaving of the rotor and insures operation at high speed in a fixed plane. In so forming the rotor, it may be of extremely light weight so as to reduce to a

2

minimum the extra load placed upon the regular sewing machine motor. Moreover, the centrifugal forces resulting from high speed rotation of the rotor element are held within permissible limits. The construction of the blower as a whole is such that it is adapted for use in connection either with a clockwise or a counter-clockwise driven motor.

Another object of the invention is to provide a blower unit which may be readily mounted on a conventional sewing machine motor with suitable provisions for adjustment, enabling the housing to be correctly aligned in relation to the rotor, and with provisions for the axial shifting of the rotor incident to the clutching and declutching of the member driven by the motor. A feature of the invention in this connection is the provision of suitable devices, including an adjustable support, for mounting the blower on the conventional motor and clutch unit of existing machines without the necessity of modifying this unit. The construction is such, moreover, that wear of the parts, such as the clutching faces, may be readily compensated by appropriate adjustment of the blower mounting devices. This enables application of the improved blower unit to existing motor and clutch units regardless of the condition of wear of the parts and at the same time allows for future wear.

A further object of the invention is the provision of suitable blower mounting means adapted for ready disconnection of the blower housing from its support, thereby enabling the removal and replacement of the sewing machine driving belt. This construction is such that the blower housing may be quickly removed from the support and restored to its original, definite position in relation thereto, without the necessity of readjusting the support or the housing in relation to the rotor.

A still further object of the invention is the provision of convenient, simple and inexpensive means for delivering the blast of air developed by the blower to the region in which the needle or needles of the machine operate. A feature of the invention, in this connection, is the provision of a discharge conduit capable of being shifted readily from an active to an inactive position and vice versa. This enables ready access to the various portions of the machine for purposes of inspection, attention and repair and permits removal of the machine from its normal operating position. A further feature of this phase of the invention is the provision of a suitable connection between the blower and the shiftable discharge conduit which permits appropriate adjustment of the driving motor in relation to the supporting table incident to the maintenance of proper belt tension.

Other objects, features and advantages of the

invention will appear from the detailed description of an illustrative embodiment of the same which will now be given in conjunction with the accompanying drawings, in which:

Fig. I is a front elevation of a sewing machine on a supporting table, showing the improved air discharge conduit in association therewith, said conduit being shown in active position in full lines and a portion of the same being shown in inactive position in broken lines.

Fig. II is complementary to Fig. I and shows, in elevation, the driving motor and associated devices beneath the supporting table on which the sewing machine is mounted.

Fig. III is an end elevation of the motor and sewing machine viewed from the belt pulley end of the machine, a portion of the table and a portion of the blower housing being broken away for clearness of illustration.

Fig. IV is a detail view in horizontal section along the line IV—IV of Fig. III, showing the connection between the blower and discharge conduit.

Fig. V is a similar horizontal sectional view along the line V—V of Fig. III.

Fig. VI is an enlarged detail view, partly in plan and partly in section along the line VI—VI of Fig. III, showing the blower and the means for mounting the same on the motor and clutch unit.

Fig. VII is an enlarged, horizontal section along the line VII—VII of Fig. III, showing a detail of the conduit mounting means.

Fig. VIII is a sectional elevational view along the line VIII—VIII of Fig. II.

Fig. IX is an exploded detail view, in plan, of the separate components which are united to form the main central member of the blower housing.

Fig. X is a view of said member of the housing with its components permanently united and

Fig. XI is a plan view of one of the end plates of the housing.

Referring now to the drawings, there is illustrated a sewing table 1 on which is mounted a sewing machine of any suitable construction. This machine, as best illustrated in Fig. I, is provided with a work support 3 over the surface of which the work is fed as it is operated upon by appropriate stitch-forming mechanism, including one or more vertically reciprocable needles 4. It will be understood that appropriate complementary stitch-forming means are provided beneath the work support 3 to cooperate with the needles as they pass through the work on the support. The needles 4 are carried by a needle bar 5 mounted for vertical reciprocation in a needle head 6 at the free end of an overhanging arm 7 extending laterally from a vertical standard 8 forming a portion of the sewing machine frame. Power is supplied to the sewing machine for the operation of the stitch-forming devices through a combined pulley and hand-wheel 9 secured to the outer end of a main drive shaft extending through the wall of the machine frame. The connections from this main drive shaft to the various operating devices of the machine may be of any conventional or known construction, such as disclosed, for example, in the patent to Thompson et al. No. 2,107,918, granted Feb. 8, 1938. The pulley 9 is connected by a suitable belt 10 with the driven pulley 11 (Fig. II) of an electric transmitter or motor and clutch unit, designated generally by the reference numeral 12. This transmitter unit may be of any suitable, known construction but for purposes of illus-

tration the invention has been shown in combination with a motor and clutch unit of the type shown and described in the patent to Max T. Voigt, No. 2,037,644, granted April 14, 1936.

Briefly, this unit comprises an electric motor 13 secured to one end of a main frame member or housing 14 adjustably carried by the under surface of the table 1 through suitable mounting means to be hereinafter described. Within the housing 14 there is provided a flywheel which is secured to the end of the motor shaft in the manner disclosed in said Voigt patent. There is also provided within the housing 14 an axially shiftable clutch member having a conical surface adapted to be engaged with a complementary friction surface on the flywheel whenever the sewing machine is to be operated and having another face adapted to be engaged by a braking surface within the housing 14 whenever the clutch is disengaged. This clutch construction is fully disclosed in the Voigt patent. The shiftable clutch member above mentioned is secured to a shaft 15 (Fig. VI) which is adapted to be shifted axially, to engage and disengage the clutch, by the operation of a lever 16. The latter is pivoted at 17 upon a lug 18 projecting from an end plate 19 secured to the end of the housing 14, in a manner to be described. The upper end of the lever 16 is bifurcated and its branches 20 extend upwardly at opposite sides of a collar 21 extending forwardly from the end plate 19 around the shaft 15. Each branch 20 is forked or otherwise formed at its upper end to engage a projection 22 extending radially outward from a sleeve 22a slidably axially within the collar extension 21 and suitably connected with the shaft 15 to impart endwise shifting movements to the latter. Projections 22 extend through slightly elongated slots in the collar extension 21 to permit the operation of the lever 16 and the axial shifting of the shaft 15 in the manner described. The lever 16 is normally drawn by a spring 23 into the position indicated in Fig. II, in which the shaft 15 is held toward the right to disengage the driving faces of the clutch and engage the braking faces hereinbefore mentioned. Operation of the lever 16, in opposition to the spring 23, may be effected in any suitable way, either manually or by a foot treadle connected by a link 24 with the free end of the lever. The pulley wheel 11 is secured to the shaft 15 and is driven thereby upon engagement of the driving faces of the clutch. In engaging and disengaging the latter the pulley 11 is shifted axially to a limited extent with the shaft.

Referring particularly to Figs. II and III, the housing 14 is pivotally supported at 25 upon a bracket 26 secured to the under surface of the table 1. For this purpose the top of the housing 14 is provided with a plate 27 having a rearward and downward extension which receives the pivot pin 25. The forward end of the plate 27 is angled upwardly and is bifurcated to receive a screw-threaded stud 28 pivotally connected at 29 to the bracket 26. By appropriate adjustment of the nuts 30 along the stud 28, the axis of the housing 14 may be lifted or lowered slightly and the tension of the belt 10 may be varied. So also, by removal of the stud 28 from the forked extension of the plate 27, the motor unit may be lifted to assist in the removal and replacement of the belt or the motor may be swung downwardly to facilitate inspection and repair.

The end plate 19 is secured to the housing 14 by means of a series of screw-threaded studs 31,

the screw-threaded portions of which are of sufficient length to pass through apertures in outwardly extending ears 32 on the end plate and to engage threaded apertures in ears 33 integral with the housing 14. Nuts 34 on the studs 31 serve to retain the parts in proper assembled relation. These nuts may be appropriately adjusted to any desired positions along the studs and serve to hold the end plate firmly against the end of the housing. Adjacent the outer end of each stud 31 it is provided with an enlarged head 35, preferably of hexagonal configuration, to enable manipulation of the stud by a wrench. Beyond this enlarged head portion there is a reduced threaded portion 36 adapted to receive a nut 37. A support member 38, which is of substantially horseshoe or C-shape, as best shown in Fig. VIII, is mounted on the series of studs 31 and is clamped between the enlarged head portions 35 and the nuts 37. It will be seen that the mounting of the support member 38 is such that its position with relation to the end plate 19 and with relation to the shaft 15 may be adjusted both angularly and axially. Each stud 31 may be adjusted independently of the others, for this purpose, so as to position the outer face of the head 35 at a greater or less distance, as desired, from the end plate 19. If they are all turned to equal extents, they will cause the support member to be adjusted axially with respect to shaft 15, but if they are turned unequally they will alter the angular position of the plane of the support member with respect to the shaft.

At opposite sides of the support member 38, preferably horizontally in line with the axis of the shaft 15, there are provided threaded apertures 39 arranged to receive the threaded ends of a pair of wing-headed screws 40. These wing-headed screws are for the purpose of attaching to the support member 38 the housing of a blower unit, to be presently described.

The blower housing, in accordance with the present invention, is formed in an inexpensive manner and in a way adapting it for reversible connection with the support member 38. This permits the same blower to be applied either to a motor with a clockwise driven shaft or one with a counter-clockwise driven shaft. The housing comprises a main body member 41, which may suitably be formed from a strip of steel appropriately bent into the volute form indicated in Fig. IX. The steel strip may, for example, be about $\frac{1}{4}$ of an inch thick and $\frac{1}{8}$ of an inch wide. In lieu of steel, the strip may be formed of other metals or of appropriate plastic materials. If formed of material incapable of being bent into the desired shape, the body member may be cast or molded in any appropriate form. Parallel with the end extension 42 of the member 41 there is provided a similar extension 43 suitably spaced to form an outlet passage. This extension 43 may be welded or brazed or otherwise secured to the end 44 of the member 41. At opposite sides of the member 41, there may be attached, by welding, brazing or other means, suitable ears or lugs 45 apertured at 46 to receive the wing-headed screws 40. To each face of the main body member there is secured, by screws or the like, a disk-like member 47 conforming in outer contour with the contour of the member 41 and its extensions 42 and 43. The central portion of each disc 47 is cut out, as indicated at 48. A metal-cutting band saw may be used to form a number of the discs 47 from sheet stock in a single operation. It will thus be seen that a blower housing is pro-

vided which is of inexpensive construction and of relatively light weight. Moreover, it is of sturdy construction and at the same time occupies a minimum of space. If produced in the manner hereinabove specified, it is susceptible of manufacture in large quantities without the use of expensive tools, such as required for the production of stamped parts and the like. In attaching the blower housing to the support member 38, suitable spacing collars 49 are provided, these serving to space the housing sufficiently from the support member to allow adequate clearance for the pulley 11 and belt 10. Preferably each of the spacing collars 49 is formed with a pair of radially extending, screw-threaded apertures adapted to receive screws 50 for the attachment of a belt guard 51.

A hub extension 52 of the belt pulley 11 is provided on its outer face with a series of threaded apertures adapted to receive screws 53a for securing to the hub a rotor or impeller 55 (Fig. VI) of suitable construction. This impeller, as best shown in Figs. III and VI, is preferably formed by cutting out suitable sections from a circular disc and then bending up portions of the remaining metal or other material to form a series of vanes 55a. An ordinary metal-cutting band saw may be used to remove the portions of the original disc and also, if desired, in the formation of the disc itself from sheet stock. The material of which the impeller vanes are thus formed may suitably be sheet steel or about .050 inch thickness. In order to eliminate vibration and weaving in the operation of the rotor at high speeds, a backing disc 56 is preferably provided, this being of the same diameter as the tip diameter of the vane member. This backing disc may be of very light construction. It may suitably be formed of sheet steel of, say, .012 inch thickness. The vane member and backing disc may be secured in any suitable way, as by soldering the ends of the blades to the backing disc. A rotor of extremely light weight is thus produced and yet it is capable of developing adequate air flow for the required purposes with a minimum load upon the driving motor. While the specific dimensions of the rotor may be varied to suit the particular requirements of the blower, it has been found satisfactory, for the purposes of supplying a cooling blast of air to the region through which the needles of a sewing machine are operated, to employ a rotor having a vane tip diameter of about 6 inches, the vanes projecting from the backing disc about $\frac{5}{16}$ of an inch. It will be understood that the size and contour of the main body member 41 of the housing will be such as to provide the desired clearances with respect to the ends of the rotor vanes at all points to produce an efficient blower construction in accordance with accepted principles. It has been found that a blower constructed in accordance with the foregoing will provide an adequate supply of air for the desired needle cooling purposes without placing any appreciable additional load upon the driving motor. Thus substantially the entire power of the motor is available to carry the load imposed by the regular sewing instrumentalities of the machine operating at the increased speeds made possible by the cooling of the needles.

It will be apparent from the foregoing that a construction has been provided in which the blower housing is mounted independently of the rotor and one in which these elements of the blower may be readily adjusted relative to each other. The rotor will at all times be maintained

in fixed relation to the shaft 15 and pulley 11 while the housing may, as previously explained, be adjusted both angularly and axially with respect to these parts by appropriate manipulation of the studs 31 and nuts 34. Moreover, it will be seen that the mounting of the blower housing is such that it may be readily detached from the support member 38 by loosening of the wing-headed screws without disturbing the adjustment of the support member 38. Therefore, when the blower housing is to be reattached, it is simply necessary to insert and tighten the wing-headed screws 40. The apertures 48 in the face plates of the blower housing are of slightly larger diameter than the hub 52 of the pulley to provide adequate clearance to permit the adjustments mentioned. By forming both of the openings of the same size, it will be seen that the blower housing is made reversible so that the blower may be applied selectively or interchangeably to motor and clutch units driven either in a clockwise or in a counter-clockwise direction. This reversibility of the blower is made possible also by the relationship between the lugs 45, with their apertures 46, and the blower axis. This relationship is such that the centers of the apertures 46 are equally distant from the axis of the blower; i. e., from the centers of the openings 48 and the axis of the shaft 15. It will be understood that the opening 48 on the side of the blower housing opposite to that which is passed over the hub extension 52 serves as the air inlet for the blower.

The blower outlet is of rectangular form and is defined by the extensions 42 and 43 of member 41 together with the corresponding portions of the side plates 47. For the purpose of connecting this outlet with a conduit 53, which serves to conduct the blast of air to the region of the needle or needles, as will be presently explained, there is preferably provided a flexible member 54 which may suitably be formed of rubber, or a rubber substitute, or coated fabric, or the like. This member is adapted to form an airtight connection both with the rectangular discharge outlet of the blower and with the tubular lower end of the conduit. It may suitably be secured to the blower by means of screws 54a and may have a relatively tight sliding fit with the lower end of the conduit for purposes to be hereinafter set forth.

The conduit 53 may be formed of steel or other metal tubing or may be molded or extruded or otherwise formed of an appropriate plastic composition. It is preferably of rigid construction and is shaped to extend from a point adjacent and slightly in rear of the base of the sewing machine in the region of the vertical standard 8, at which point the conduit passes through the table 1, to a point near the zone of operation of the needle or needles. At the latter point the discharge outlet 58a of the conduit is arranged to direct a stream of cooling air downwardly along and transversely across the path of the needles above the work support. The angular disposition of the discharge end of the conduit, its distance from the needle path, its diameter or area, and other related factors are preferably in accordance with the disclosure in said pending Rubel application S. N. 433,740.

That end of the conduit which passes through the table 1 is retained by a sleeve 57 which extends upwardly through an opening 58 in the table. To facilitate assembly and adjustment of the parts, a substantial clearance is preferably

provided between the sleeve and opening, as shown in Fig. III. At its lower end the sleeve is provided with a laterally extending arm 59 adapted to be attached to the under surface of the table by means of a number of screws 60. The upper end of the sleeve 57 is reduced slightly in its outer diameter to provide a shoulder 61 upon which a split collar 62 is supported. This collar surrounds the reduced portion of the sleeve and is adapted to be clamped thereon by a screw 63 which may be turned by a small rod or bar 64 slidable freely in an aperture formed in the enlarged head 65 of the screw. The upper end of the sleeve 57 is split into four segments by means of a series of slots 66 which extend down to a point slightly below the shoulder 61. It will be understood that when the clamping collar 62 is tightened upon the split upper end of the sleeve 57 by the turning of screw 63, the split portions of the sleeve will in turn clamp the conduit 53 and retain it firmly in whatever position it may have been turned. Thus the conduit may be held in its active position with the discharge end as shown in Fig. I or it may be swung back into inoperative position whenever desired. This, for example, permits lifting or tilting of the sewing machine in relation to the table whenever required for purposes of inspection or repair. A split collar 67 arranged to be clamped upon the conduit by means of a screw 68 serves to support the conduit on the collar 62 and prevents the conduit from dropping lower in the sleeve 57.

The operation of the machine and its attachments is believed to be clear from the foregoing. Assuming the parts to be in the position indicated in Figs. I, II and III, the blower rotor will be driven whenever the sewing machine is operated under control of the clutch lever 16. Shifting of the pulley 11 and the rotor incident to the engagement of the clutch is permitted by the clearances indicated in Fig. VI. The air blast developed by the blower and delivered through the conduit 53 to the zone above the work support through which the needles operate will serve to cool the needles sufficiently to permit a substantial increase in the speed of operation of the machine on relatively heavy and tough materials. The cooling action will not only reduce needle breakages and injury to other parts of the machine but will reduce the needle thread breakages and hence minimize the loss of operating time due to re-threading.

The clearance between the backing disc 56 of the rotor and the plate 47 of the housing is sufficient to allow not only for the normal shifting of the rotor in the engagement of the clutch but also to allow for a certain amount of wear of the clutch surfaces. If the clearance becomes too small after a long period of operation, the support member 38 may be adjusted axially, toward the left in Fig. II, by appropriate adjustment of the threaded studs 31 and the nuts 34. So also, if the wear is irregular, so that the rotor is brought closer to the end plate 47 of the housing at one point or another, relative angular adjustment of these parts may be obtained by a variable adjustment of the several screw-threaded studs 31 and nuts 34.

If the driving belt should break, it may be replaced in the following manner: The flexible sleeve 54 may be disconnected either from the conduit 53 or from the outlet of the blower. To disconnect it from the conduit the latter may be unclamped and raised slightly. The blower housing may then be removed from the support 38

by removing the wing-headed screws 40. This will not permit complete removal of the housing from the machine but it will allow a new belt to be passed over the rotor of the blower and onto the pulley 11. If desired, the housing may be disconnected in this way first and the sleeve 54 disconnected subsequently. In either case the belt may then be passed upwardly through the usual opening in the table 1 and applied over the pulley wheel 9. In order to permit the belt to be passed over this pulley wheel, the motor and clutch unit may be lifted by appropriate adjustment of the nuts 30 along the stud 28 or by disconnecting this stud from the forked extension of the top plate 27. After the belt has been properly positioned, it may be given the desired tension by appropriate adjustment of the nuts 30. The flexible connection 54 may then be re-applied and the blower housing may be attached to the support 32 by the wing-headed screws 40.

While an illustrative form of the invention has been described in considerable detail, it will be understood that numerous variations may be made in the construction and arrangement of the several parts without departing from the scope and principles of the invention. The terms and expressions used herein have been used as terms of description and not of limitation. However, the term "angular adjustment" as employed in the appended claims shall be understood to mean adjustment of the angle of the axes of the parts referred to in relation to other parts as distinguished from the mere rotative position of the parts about their axes.

What I claim is:

1. In combination a sewing machine having stitch forming devices including a needle, means for operating said needle, power means including a motor and clutch unit for driving said needle operating means, said unit having a frame and a shaft journaled therein, said shaft being shiftable axially in the engagement and disengagement of the clutch of said unit, a blower having a rotor and a housing, the rotor being operatively connected with said shaft of said motor and clutch unit, a support member mounted on the frame of said motor and clutch unit for angular and axial adjustment in relation thereto, means for detachably connecting the blower housing in fixed relation to said support member, and a conduit for delivering air from said blower to the region in which said needle is operated, said angular and axial adjustment of said support member enabling proper clearance between the rotor and housing at all times.

2. In apparatus of the class described, a machine having a needle and operating means therefor a driving motor including a frame structure, a rotatable shaft journaled in said frame structure and projecting therefrom, a pulley on said shaft operatively connected with said sewing machine, a blower including a rotor operatively associated with said shaft and disposed at the opposite side of said belt pulley from said driving motor, a blower housing surrounding said rotor, a discharge conduit extending from said blower to a point adjacent the zone of operation of the sewing machine needle, and devices for securing said blower housing to said driving motor frame structure, said devices including an intermediate member between said structure and housing which is adjustably connected to one and connected in definite relation to the other, thereby enabling relative adjustment of said housing and rotor and ready detachment of said housing from

said frame structure without disturbing said adjustment.

3. In apparatus of the class described a sewing machine having a reciprocating needle, a driving motor unit therefor including a clutch, a frame end member for said motor unit, a shaft journaled in said end member shiftable endwise therein incident to engagement and disengagement of said clutch, said shaft being provided with a pulley operatively connected by a belt to said sewing machine, a series of bolts connecting said frame end member to the driving motor, a bracket member adjustably carried by said bolts, a blower rotor operatively associated with said shaft, a blower housing detachably connected with said bracket in definite position thereon and surrounding said rotor, and a conduit extending from the discharge side of said blower to a point adjacent the zone of operation of the needle of said sewing machine.

4. In combination a supporting table, a sewing machine mounted on said table, said machine having stitch forming means above said table, a motor unit beneath said table, a driving connection between said unit and said machine for operating said stitch forming means, a blower associated with said motor unit and driven thereby, and a conduit arranged to deliver air from said blower to the region of operation of said stitch forming means, said motor unit and blower being hingedly mounted on said table and adjustable relative to said table, and said conduit having relatively slidable portions enabling such relative adjustment, said blower having its discharge outlet adjacent the axis along which the blower is hingedly mounted.

5. In combination a sewing machine having a part to be cooled, a motor and clutch unit for driving said machine, said unit having a frame and a shaft journaled in said frame, a blower associated with said unit, said blower comprising a housing and a rotor, a support member, means for mounting said support member on said frame for angular and axial adjustment relative thereto, means for detachably connecting said blower housing in definite relation with said support, means for independently connecting said rotor with said shaft, and a conduit connected with said housing for delivering air to said part to be cooled.
